UNITED STATES PATENT OFFICE.

HARLO M. HERRING, OF MARSHALL, MINNESOTA.

AIR-SUPPLYING APPARATUS.

1,331,473.

Specification of Letters Patent. Patented Feb. 17, 1920.

Application filed May 21, 1919. Serial No. 298,738.

To all whom it may concern:

Be it known that I, HARLO M. HERRING, a citizen of the United States, residing at Marshall, in the county of Lyon and State of Minnesota, have invented certain new and useful Improvements in Air-Supplying Apparatus, of which the following is a specification, reference being had to the accompanying drawings.

10 This invention relates to mechanisms used for supplying what is termed free air to automobileists for the purpose of inflating the tires of their machines.

In apparatus of this character the air is supplied by means of a flexible hose, and air hose almost invariably leaks. This means a constant loss of air pressure in the supply tank which requires a more or less constant operation of the power pump to keep up the pressure, particularly inasmuch as the flexible hose, lying as it does on the ground or sidewalk, is liable to be broken and punctured.

The general object of my invention, therefore, is to provide means for reducing this loss by leakage by cutting off the passage of air to this flexible hose when it is in use, and to this end to provide means for controlling the passage of compressed air from the supply tank so as to permit the air to be supplied, that is the air line opened from the supply tank for a certain definite length of time, and then cause the air to be cut off and remain cut off until the main controlling valve is again operated.

And a further object is to provide a mechanism of this character wherein oil or other liquid is forced into a cylinder by the opening of the main valve, which opening of the main valve also causes a discharge of air from the tank, and that when the tank has been filled with oil, the return movement of the oil in the tank will cause eventually the closing of the main controlling valve, thus causing the pipe line leading from the air tank to the car to be kept open during the time that the tank is filling with oil and the oil is being discharged therefrom, and then automatically cutting off the supply of air until the main valve is again operated.

Other objects will appear in the course of the following description.

My invention is illustrated in the accompanying drawings, wherein:

55 Figure 1 is a vertical sectional view of

an air controlling apparatus constructed in accordance with my invention;

Fig. 2 is a fragmentary vertical sectional view showing the position of the parts when the piston is raised: 60

Fig. 3 is a detail sectional view of the valve 18; and

Fig. 4 is a longitudinal sectional view of the valve 32.

Referring to these drawings, 10 designates an oil containing chamber or tank which is mounted in any suitable manner, as upon the bottom of a casing 11, this tank having a filling opening 12, having an air cock 13 permitting the tank to be filled with oil, 70 either completely or to a certain level, and allowing the escape of air for this purpose. The bottom of the oil tank 10 is connected by a pipe 14 to the lower end of a cylinder 15, and above this pipe 14 the cylinder 15 is 75 connected by a pipe 16 to the tank 10. The pipe 14 is provided between its ends with a check valve 17 opening toward the cylinder 15 but closing upon back pressure. The pipe 16 is provided with a regulating valve 80 18 of any suitable construction, which is controlled by a handle 19. This regulating valve may be so adjusted as to control the rapidity of passage of the oil from the cylinder 15 back into the tank 10. Disposed 85 within the cylinder 15 is a piston 20 having a piston rod 21 which extends up through the cylinder and out through a suitable stuffing box 22 at the top of the cylinder.

A pipe 23 extends out of the housing or 90 casing 11 and is adapted to be connected as by the nipple 24 to an air supply tank whereby the air is kept at a certain pressure. From the pipe 23 extend two branches 25 and 26. The pipe line 25 leads to a rubber 95 hose, which rubber hose carries upon it the usual valve whereby it may be connected to the tire valve of the automobile. The branch 26, however, leads to a valve casing 27 supported on brackets 28 and having therein a 100 valve 29 provided with a handle 30 by which the valve 29 may be rotated to an open position. The valve 29 is normally urged to its closed position. From the valve casing 27 extends a pipe 31 which opens into the upper 105 portion of the oil tank 10.

Disposed in the length of the branch pipe 25 is a rotatable valve 32, having an arm 33 connected by a contractile spring 34 to the upper end of the piston rod 21 at the point 110

35. Two relatively light springs 36 are attached at their lower ends to the bottom of the cylinder 15 or to any other suitable portion thereof, and are connected at their upper ends to the piston rod at the point 37, thus resisting an upward movement of the piston rod. The pipe 23 may carry a branch 38 connected to a pressure gage 39.

- Now when the valve 27 is opened by rotating the handle 30 to a depressed position, communication is established between the air supply tank and the upper portion of the oil tank 10 through the pipe 23, branch 26, and pipe 31. Oil will, therefore, be forced under pressure out through the tank 10, through the pipe 14, past the valve 17, and into the cylinder 15, raising the piston 20. This forces the piston 20 upward, together with the piston rod 21, and carries 20 upward that end of the spring 34 which is connected to the piston rod at the point 35. After the end of the spring 34 reaches the point *a* where it is opposite the extremity of the arm 33, the spring 34 exerts a gradual 25 lifting upon the free end of the arm 33, thus causing the arm 33 to move upward, opening the valve 32, until the arm reaches the stop pin 40, at which time the piston has lifted to its full extent. The opening of the valve 30 30 allows air to pass through pipe 25 to the hose line which is connected to the inflating valve. As soon as the piston is lifted its full amount, the handle 30 of the valve 29 is released, whereupon it automatically flies 35 up and closes the valve. After the handle 30 is released and the valve 29 is closed, communication between the upper portion of the oil tank 10 and the air supply is cut off and, therefore, the two springs 36 tend to pull the 40 piston 20 downward.

Upon a downward movement of the piston 20, the check valve 17 closes, thus preventing a return of the oil from the cylinder 15 to the tank 10 through the pipe 14, and, therefore, the oil must pass backward or return to the oil tank through the pipe 16. Thus, the oil returns to the tank 10 with a degree of rapidity depending upon the regulation of the valve 18. This valve is so regulated 50 or timed that the oil will take two minutes, for instance, to pass from the cylinder 15, back through the valve 18 into the oil chamber or tank 10, thus yieldingly resisting the downward movement of the piston and the 55 consequent return of the valve 32 to its closed position. Thus, for instance, the valve 32 may be caused to remain open for a period of two minutes or for any other desired period. The arm 33 is stopped when the valve is 60 fully closed by engagement with the stop 38^a. Preferably, a signal is mounted upon the casing, so designed that when the piston has reached its full upward movement, the signal will be displayed reading "Full Air", 65 or words to that effect, and when the piston

has been lowered to its full extent, the signal will read "No Air", or words to that effect. Thus, for instance I have shown a member 41 pivoted intermediate its ends and having the said signals on opposite ends of the member. 70 Normally, the sign, "No Air," will be displayed, but when the piston rod rises to its full extent, the upper end of the piston rod will strike same portion of the member 41 and force it to a position where the sign 75 "Full Air" will be displayed. A chain 42 is attached to this member 41, this chain being ordinarily slack, but when the piston has descended to its full extent, this chain will be tightened, drawing the member 41 to a 80 position where the words "No Air" will be displayed. These signs, it will be of course understood, appear at the outside of the box or casing where they will be visible to the operator. The air cock 13 is left open 85 slightly at all times so as to let air escape as the oil enters the oil tanks or chamber 10 upon the backward stroke of the piston.

This valve is to be placed in any desired position outside of an establishment offering 90 free air to the public for the purpose of inflating automobile tires, thus doing away with the necessity of using an expensive and extra electric motor and pump. The device is automatic in its operation and may be used 95 in connection with the ordinary air supply tank which is to be found in practically all establishments offering free air to the public for tire inflating purposes.

It will be noted that as the piston rod 21 100 rises the contractile spring 34 will exert no such pull on the arm 33 as to cause it to move to an open position until the piston rod has risen to the point *a*. While the piston rod is moving from the point *a* to the point 105 *b*, the contractile spring 34 is exerting a force to cause the quick and sudden opening of the valve and that upon a reverse movement of the piston rod, the contractile spring 34 will exert no action upon the arm 33 until 110 the upper end of the piston rod is lowered to the position *c*. Then the spring passes the center of the arm 33 and exerts a pulling action upon the arm, which causes the valve to suddenly close.

While I have illustrated a preferred form of my invention, and one which I have found to be thoroughly effective in practice, yet I do not wish to be limited thereto, as it is obvious that many changes might be made 120 therein without departing from the spirit of the invention.

I claim:—

1. Means for controlling the delivery of compressed air comprising a liquid tank 125 having a connection at its upper end to a source of fluid under pressure, said connection being provided with a normally closed controlling valve, a cylinder, means connecting the lower end of the liquid tank with 130

the cylinder and permitting the movement of liquid from the tank into said cylinder but retarding the return movement of liquid from the cylinder into the tank, a fluid delivery pipe connected to the source of compressed fluid, a delivery valve mounted therein, a piston in the cylinder, and means connecting the piston with the fluid valve to cause an opening of the fluid valve upon an outward movement of the piston due to the passage of liquid into the cylinder but causing the closing of the air valve when the piston has descended a predetermined amount.

2. In an apparatus of the character described, the combination with a source of fluid under pressure and a delivery pipe for said fluid, of a delivery valve controlling passage through the delivery pipe, manually controlled means shiftable in one direction to cause an opening movement of the valve, means acting to reversely shift said manually controlled means, and means acting automatically to hold the valve open a predetermined time after the reverse movement of the manually controlled means and then close said delivery valve.

3. In an apparatus of the character described, the combination with a source of fluid under pressure and a delivery pipe leading therefrom, of a delivery valve controlling passage through said pipe, a liquid receiving cylinder having a piston, a piston rod, means holding the fluid delivery valve closed until the piston and piston rod have traveled in one direction a predetermined distance through the cylinder and then causing the quick opening of the valve, and holding the delivery valve open until the piston and piston rod have traveled a predetermined distance in the other direction through the cylinder and then causing the quick closing of said valve, fluid pressure actuated means for forcing liquid into said cylinder behind the piston to cause the shifting of the piston in a direction to open said delivery valve, manually controlled means for establishing connection between the source of fluid under pressure and the said fluid pressure actuated means, and means retarding the movement of the piston and piston rod in a direction to cause the closing of said valve.

4. In an apparatus of the character described, the combination with a source of fluid under pressure and a supply pipe leading therefrom, of a delivery valve controlling passage through said supply pipe, a liquid containing tank, a pipe leading from the source of fluid under pressure into said liquid tank, a manually actuatable valve controlling the passage of the fluid into said liquid tank, a cylinder having therein a piston and a piston rod, a connection between the liquid tank and one end of the cylinder, permitting the passage of the liquid from the

tank into the cylinder behind the piston in one direction but retarding the passage of liquid in the opposite direction from the cylinder into the tank, and means for causing the sudden opening of the valve in said supply pipe when the piston has shifted a predetermined distance under the action of said liquid, said means causing a closing of the valve when the piston has shifted in a reverse direction a predetermined distance.

5. In an apparatus of the character described, the combination with a source of fluid under pressure and a supply pipe leading therefrom, of a delivery valve controlling the passage through said supply pipe, a liquid containing tank, a pipe leading from the source of fluid under pressure into said liquid tank, a manually actuatable valve controlling the passage of the fluid into said liquid tank, a cylinder having therein a piston and a piston rod, a connection between the liquid tank and one end of the cylinder, permitting the passage of the liquid from the tank into the cylinder behind the piston in one direction but restricting the passage of liquid in the opposite direction from the cylinder into the tank, a spring resisting the outward movement of the piston and piston rod, an arm extending from the supply delivery valve, a contractile spring connected to the piston and to said arm, the point of connection between the piston and the spring moving across the pivotal center of the arm whereby a movement of the piston rod out of the cylinder a predetermined distance will cause the spring to pass the center of the arm and delivery valve and cause the sudden opening of the valve and a return movement of the piston rod will cause a sudden closing of the delivery valve after the said point of connection has passed the center of said valve arm.

6. In an apparatus of the character described, the combination with a source of air under pressure, of a liquid tank having an air escape valve in its upper portion, a cylinder having therein a piston, a piston rod extending from the piston upward through the cylinder, a tubular connection leading from the lower end of the liquid tank into the lower end of the cylinder and having therein a check valve, a tubular connection leading from the lower end of the cylinder into the tank and having therein a manually regulatable passage, springs resisting the upward movement of the piston rod, a tubular connection between the upper end of said tank and a source of air under pressure, a valve in said connection normally urged to a closed position but manually rotatable to an open position, a rotatable delivery valve in the supply pipe having a radially extending arm, the arm extending in a direction away from the path of movement of the piston rod, and the piston rod moving from a

point below said arm to a point above the arm, and a contractile spring connecting the extremity of the arm with the piston rod.

7. In an apparatus of the character described, the combination with a source of air under pressure, of a liquid tank having an air escape valve in its upper portion, a cylinder having therein a piston, a piston rod extending from the piston upward through the cylinder, a tubular connection leading from the lower end of the liquid tank into the lower end of the cylinder and having therein a check valve, a tubular connection leading from the lower end of the cylinder into the tank and having therein a manually regulatable passage, springs resisting the upward movement of the piston rod, a tubular connection between the upper end of said tank and a source of air under pressure, a valve in said connection normally urged to a closed position but manually rotatable to an open position, a rotatable delivery valve in the supply pipe having a radially extending arm, the arm extending in a direction away from the path of movement of the piston rod and the piston rod moving from a point below said arm to a point above the arm, and a contractile spring connecting the extremity of the arm with the piston rod, and a signal shifted in one direction by a movement of the piston rod to its fully raised position and shifted to another position upon the return of the piston rod to its lowered position.
8. In an apparatus of the character described, the combination with a source of fluid under pressure, a delivery pipe and a valve therein, of valve operating means movable in two directions and operatively connected to the delivery valve to open it when said means has fully moved in one direction and to close it when said means has fully moved in the other direction, manually operable means for causing the first named movement of the valve operating means, automatically acting means for causing a reverse movement of the valve operating means, and means retarding said reverse

movement of the valve operating means to thereby cause the delivery valve to remain open a predetermined length of time.

9. In an apparatus of the character described, the combination with a source of fluid under pressure and a delivery pipe, of a liquid containing chamber, a branch pipe leading from the delivery pipe into said liquid containing chamber, a delivery valve in the delivery pipe, manually operable means in said branch pipe for establishing or disestablishing connection between the liquid containing chamber and the source of fluid, and means operatively connected to the delivery valve and actuated by the discharge of liquid from said chamber under the action of the fluid admitted to the chamber from said source, causing the valve to open, means permitting the discharge of fluid from the chamber after the connection between the chamber and the source of pressure has been disestablished to thereby permit the reverse movement of the valve operating means to cause the closing of the valve.

10. An apparatus of the character described including in combination a source of fluid under pressure, a delivery pipe therefrom, a delivery valve in the delivery pipe controlling the passage of fluid therethrough, a manually controlled member movable in one direction from an initial position, means urging said member toward its initial position, said member when it has fully moved in a direction away from its initial position causing the opening of the valve, and when it has returned to its initial position causing the closing of the valve, means for retarding the speed of movement of said member to its initial position, and a signal movable to a display position upon a full movement of said member in a predetermined direction.

In testimony whereof I hereunto affix my signature in the presence of two witnesses.

HARLO M. HERRING.
